STACKING MACHINE

Roger L. Griffin, Marblehead, Mass., assignor, by
mesne assignments, to Swift & Company, Chi-
cago, Ill., a corporation of Illinois

Application January 3, 1948, Serial No. 403

20 Claims. (Cl. 214—6)

1
This invention relates to a machine for stacking frames and the like relatively flat supporting members which, due to their size, shape, and/or weight, are difficult to handle manually.

In the processing of leather and other types of sheet materials, particularly those of irregular shape, it is the practice to support the sheet material within a frame or on a relatively flat board or the like surface and while thus supported to treat the exposed surface of the sheet material as by applying a coating composition or finish thereto. For example, in the manufacture of patent leather, the processed skins are stretched out and supported in stretched condition within the confines of a rectangular frame and while thus supported a coating of lacquer or other suitable finish is applied to the outer face, after which the frame is transferred to an oven where the coating is dried in accordance with the requirements of the situation.

Although such coating may be applied manually, it is usually done while the frame is being conveyed beneath a battery of spray nozzles which traverse the entire surface of the skin, and provision must be made for receiving the frames as they are discharged from the conveyor, stacking them and transporting the stacks to the oven. Since such frames are usually of the order of 10' to 15' square, manual handling would not only require the services of several employees, but also would be time-consuming, expensive and generally inefficient.

The principal object of the present invention is to provide a frame-stacking machine which is adapted to receive the frames and automatically stack them so that the stack can readily be transported or conveyed to a drying oven or other desired location, as the case may be.

More specific objects are to provide a stacking machine which operates automatically in conjunction with a conveyor so as to receive the frames discharged therefrom, then stack a predetermined number of such frames and position the stacked frames for removal so that the stacking operation may be continued without interruption; and to provide control means for such a machine effective to arrest the operation of the stacking mechanism in the event a frame is not properly transported thereto or in the event a stack of frames is not removed from the machine after a predetermined period of operation.

Further objects relate to various features of construction and will be apparent from the consideration of the following description and accompanying drawings, wherein:

Fig. 1 is a top plan view of a frame-stacking

2
machine constructed in accordance with the present invention, but with certain parts of the framework, control switches, etc., removed to show the operating mechanisms more clearly;

5 Fig. 2 is a side elevation of the machine with certain parts removed;

Fig. 3 is an enlarged vertical section on the line 3—3 of Fig. 1, showing the frame-lifting mechanism in elevated or uppermost position;

10 Fig. 4 is an enlarged vertical section on the line 4—4 of Fig. 1, showing the frame-lifting mechanism in lowermost position;

Fig. 5 is an enlarged vertical section on the line 5—5 of Fig. 1;

15 Fig. 6 is an isometric view of one of the lifting carriages;

Fig. 7 is a fragmentary top plan view of the upper right-hand corner of the machine as viewed in Figs. 1 and 2;

20 Fig. 8 is a rear view of the counter mechanism and associated parts;

Fig. 9 is an enlarged section on the line 9—9 of Fig. 7;

Fig. 10 is a front view of the counter;

25 Fig. 11 is a side elevation showing the frame-lifting, frame-transfer and stacking-lifting mechanisms and associated operating mechanisms and controls therefor;

Fig. 12 is a longitudinal section through the 30 control valve; and

Fig. 13 is a wiring diagram of the electrical control system.

In accordance with the present invention the frame-stacking machine comprises a frame-35 work or other suitable structure defining an elevator well having at or adjacent its lower end an entrance opening to receive a frame or the like support and at or adjacent to its upper end a discharge opening through which a stack of

40 frames may be removed. Between the entrance and discharge openings there is provided stationary supporting means for holding a stack of frames, and below the stack-supporting means is a frame-lifting and transfer mechanism opera-45 tive to receive a frame through the entrance opening, elevate and transfer it to the stack-sup-
porting means, thereby building up a stack of frames between the entrance and discharge openings. There is also provided a stack-lift-
ing mechanism operative to elevate the stack of frames to the level of the discharge opening so

50 that the entire stack may be removed by a fork truck, conveyor or other suitable means and transferred to an oven or other location, as de-
55 sired.

In addition, control means are provided for

3

automatically operating a frame-lifting mechanism in response to the receipt of a frame to be stacked and there may also be provided control means for effecting the operation of the stack-lifting mechanism after a predetermined number of frames have been transferred to the stack-supporting means, thereby permitting the stacking operation to continue without interruption.

The accompanying drawings illustrate a stacking machine designed for stacking rectangular frames carrying processed skins, such as patent leather, which have been conducted through a spray-coating machine by a conveyor having its discharge end juxtaposed to the entrance opening of the stacking machine so that the conveyor discharges the frames directly into the stacking machine. In this particular embodiment the frames are to be stacked in groups of twenty and after having built up a stack of twenty frames, the stack-lifting mechanism is automatically brought into operation to elevate the stack to the level of the discharge opening so that another stack of twenty frames may be built up without interruption.

Referring to Figs. 1 to 4, the machine comprises a framework of structural steel members

so that another stack of twenty frames may be automatically brought into operation to elevate the stack to the level of the discharge opening so that another stack of twenty frames may be built up without interruption. 25

Referring to Figs. 1 to 4, the machine comprises a framework of structural steel members including vertical channels 1, 2, 3 and 4 and

the shafts 32 in one direction and then in the opposite direction.

The opposite ends of each of the shafts 32 carry a relatively large sprocket 50 juxtaposed to a smaller sprocket 52 (Fig. 5) and vertically aligned with each of the sprockets 50 and 52 are corresponding sprockets 54 and 56 rotatably mounted on stub shafts carried by pillow blocks 58 which are supported on a pair of horizontal structural members 60, 61. The corresponding vertically aligned sprockets carry chains 64 and 66 which are respectively connected with horizontally aligned frame-lifting carriages 68 and horizontally aligned frame-transfer carriages 70 (Figs. 3 and 5).

18   Mounted on upright channels 72 and 73 at a
level above the entrance opening E are four
pairs of stationary stack-supporting latch dogs
14 arranged one at each side of the chains 64
20 and 66, as shown more clearly in Fig. 3. Each
latch dog comprises an inwardly projecting flat
plate or shelf 75 integrally joined by a pair of
webs 76 to a sleeve 78 pivotally mounted on a
stud carried by a supporting bracket 80 which
25 is fixed to one of the channels, as shown in Figs.
3 and 5. An inwardly projecting arm 82, in-

position projecting into the path of vertical

1. 100 frame carried by the frame-lifting

travel of a frame caused by excitation and arrangement

mechanism, the *hypothesis* has sprung

THE CONVENTIONALITY OF

engaging position, as shown in Figs. 3, 5 and 6. The inner edge of the plates 90 and 91 are recessed above the shelf 98 so as to permit the latch dog to be swung upwardly out of the path of travel of a frame F.

With this construction and arrangement of parts the four frame-lifting carriages move in unison from their lowermost or frame-receiving position (shown in the full lines of Fig. 5 and the broken lines of Fig. 11) to elevated or frame-transfer position (shown in the full lines of Fig. 11), and simultaneously the four frame-transfer carriages 70 move downwardly. As the carriages 68 pass the carriages 70, the latch dogs of the latter are swung upwardly by the engagement with the sides of the frame F supported on the carriages 68, after which the latch dogs swing back to normal position, thus completing the first half cycle of the frame-lifting and frame-transferring operation. During the second half cycle the carriages 68 move downwardly while the carriages 70 move upwardly and as the carriages pass each other the frame supported by the carriages 68 is transferred to the carriages 70 which elevate it to a level above the stationary dogs 74, as shown in Figs. 4 and 5. During this half cycle the sides of the frame F swing the stationary dogs 74 upwardly and after passing by the dogs, the latter drop back to a normal position. After completion of the second half cycle the first frame transferred to the carriages 70 is temporarily held in elevated position above the level of the stationary latch dogs 74, as shown in Fig. 5, but during the next half cycle the frame-transfer carriages 70 descend and thus transfer the frame F to the stationary dogs, after which the carriages 70 pick up another frame from the carriages 68. As the second frame F-2 (Fig. 11) is being lifted it engages the first frame F-1 previously transferred to the stationary or stack-supporting dogs 74 and both frames F-1 and F-2 are lifted by the carriages 70 and temporarily supported at the uppermost level of the carriages 70. The next downward movement of the carriages 70 (second half cycle) transfers both frames to the stationary dogs 74, after which a third frame F-3 is picked up by and transferred from the frame-lifting carriages 68, and the operation is repeated until the desired number of frames have been transferred and stacked.

The frame-lifting and transfer mechanisms are actuated by the piston 43 within the cylinder 44, as previously explained, and the operation of the piston is automatically controlled by a valve system (Fig. 11) including a three-way valve 110, suitably mounted at the rear of the framework with its operating arm or lever 111 positioned to be engaged by the leading edge of the frame F as it approaches the end of the elevator well, as indicated in Figs. 4 and 11. One branch of the valve 110 is connected with an air supply line 112, the second branch is connected by a line 114 with one port of a control valve 115 (Figs. 11 and 12) and the third branch provides an exhaust 116 to the atmosphere.

Another three-way valve 120 is suitably secured to the framework with its operating arm or lever 121 juxtaposed to the face of the sprocket 37 so as to be engaged by a pin 122 projecting therefrom when the piston 43 approaches the end of its first stroke. One branch of the valve 120 is connected by a T 124 to the air supply line 112, the second branch is connected by a line 125 with a second port of control valve 115

and the third branch provides an exhaust 126 to the atmosphere. One end of a line 130 is connected by a T 131 with the air supply line 112 and its opposite end is connected to a third port of control valve 115.

The control valve 115 (Fig. 12) comprises a cylinder having at opposite ends ports to which the lines 114 and 125 are connected, a central port to which the line 130 is connected and 10 which communicates with an internal annular groove 134, exhaust ports 135 and 136 at each side of the central port and ports 137 and 138 diametrically opposite ports 135 and 136, respectively. The ports 137 and 138 are connected by 15 lines 140 and 141, respectively, to the opposite ends of the cylinder 44. A piston valve member 142 is slidable within the cylinder 115 and adjacent to each end the piston is formed with annular grooves 144 and 145, and between the 20 grooves 144 and 145 is a longitudinally extending groove 146.

The construction and arrangement of parts are such that when the valve member 142 is in one position, as shown in Fig. 12, the groove 144 25 provides a communication between ports 135 and 137 and the groove 146 provides a connection between the line 130 and the line 141. Hence, air in the supply line 112 may flow through the line 130, grooves 134 and 146 and port 138 into the line 141 which conducts it to one end of the cylinder 44, thereby effecting movement of the piston 43 to one end of the cylinder, as shown in Fig. 11. The air displaced by such movement is conducted through the line 140, groove 144 and out exhaust port 135. When the valve member 30 35 40 45 50 55 60 65 70 75 142 moves to the other end of the cylinder, port 135 is closed and the groove 145 provides a communication between line 141 and exhaust port 136, and grooves 134 and 146 provide a communication between the line 130 and the line 140, thus transferring the air supply to the opposite end of the cylinder 44 and thereby effecting movement of the piston 43 back to its first position, the air displaced by the return movement of the piston being exhausted through line 141, groove 145 and port 136.

The movement of the valve member 142 and hence the operation of the piston 43 is controlled by the operation of valves 110 and 120, it being noted that when a frame F trips lever 111, the valve 110 connects supply line 112 with line 114, thus causing valve member 142 to travel toward one end of the cylinder to initiate the first half cycle, and as the first half cycle is about to be completed, the pin 122 trips the lever 121 of valve 120 to connect supply line 112 with the line 125, thus causing valve member 142 to travel toward the opposite end of the cylinder 115 to initiate the second half cycle.

Mounted at the front or receiving end of the framework just below the entrance opening E is a normally closed switch S4 (Figs. 3 and 11) having its operating arm positioned so as to be engaged and thus opened by the leading edge of a frame F as it enters the elevator well, and at a corresponding position at the rear of the framework is another normally closed switch S3 (Fig. 4) having its operating arm positioned to be engaged and thus opened by the leading edge of the frame F as it approaches the end of the elevator well, in which position the trailing edge of the frame F disengages the operating arm of switch S4 thus closing the switch. With the frame properly positioned within the elevator well, the switch S4 remains closed but switch S3

is held open until the frame is lifted by the carriages 68, whereupon the switch S3 closes. The two switches are connected in a circuit, hereinafter described, which controls the operation of the conveyor motor CM (Fig. 13) and the stack-lifting mechanism.

The stack of frames F transferred to the stack-supporting dogs 74 is periodically elevated by a stack-lifting mechanism 150 (Figs. 2, 3 and 11) the operation of which is controlled by a counter mechanism 152 (Figs. 7-10) actuated by the frame-lifting mechanism. The counter mechanism 152 is mounted on a base plate 154 supported by the horizontal frame members 60 and 61 and comprises a shaft 155 rotatably mounted in pillow blocks 156 and 157. The outer end of the shaft 155 carries a pointer 160 cooperating with a dial 161 fixed to the base 154, and the inner end of the shaft carries a ratchet wheel 162 having twenty notches. A ratchet lever 164 is rotatably mounted on the inner end of the shaft 155 and pivotally mounted on this lever is a pawl 165 yielding held in operative engagement with the teeth of the ratchet wheel by a small tension spring 166, as shown in Fig. 8. The outer end of the lever 164 carries a laterally projecting pin 168 engageable with a lug 170 carried by the adjacent chain run 64, the construction and arrangement of parts being such that as the carriages 68 return from their uppermost position the lug 170 engages the pin 168 to swing lever 164 through an angle sufficient to advance the ratchet wheel 162 one notch. A small leaf spring 172 is secured to a bracket 174 mounted on the base 154 with its free end engaging the teeth of the ratchet wheel 162, as shown in Fig. 8, to prevent back travel.

Mounted between the pillow blocks 156 and 157 are upstanding brackets 174 and 175 which support a normally open switch S1 and a normally closed switch S6, respectively, both of which have inwardly extending actuating levers 176 and 177 offset with respect to each other, as shown more clearly in Fig. 9. Mounted on the shaft 155 in alignment with the levers 176 and 177 are operating arms 180 and 181 arranged so that the arm 180 closes switch S1 when the twentieth frame F has been transferred, but opens the switch S1 when the next frame has been transferred, and the arm 181 opens switch S6 when the eighteenth frame has been transferred, but closes the switch S6 when the nineteenth frame has been transferred. With this construction and arrangement of parts, the descending movement of chains 64 effecting the transfer of a frame F from carriages 68 to carriages 70 operates the counter mechanism 152 and when the eighteenth frame has been transferred, switch S6 opens and remains open until the nineteenth frame has been transferred (for reasons hereinafter to be pointed out), and when the twentieth frame has been transferred S1 closes to operate the stack-lifting mechanism 150 presently to be described.

The stack-lifting mechanism 150 comprises two pairs of vertically aligned shafts 190 and 191 carried by pillow blocks mounted on the upright channels 1-4 at the corners of the elevator well W. The lower shafts 190 are horizontally aligned at a level slightly below that of the stationary dogs 75 and the upper shafts 191 are horizontally aligned at a level slightly above the lower part of the discharge opening D, as shown in Figs. 2, 3 and 11. Adjacent to their opposite ends the shafts 190 and 191 carry sprockets 194 and 195, respectively, and chains 196 and 197 ex-

tend about each pair of sprockets. At equally spaced portions chains 196 and 197 support the ends of transversely extending T-bars 198 which are so positioned as to engage and lift a stack of frames supported on the stationary dogs 75 when the sprockets are rotated. Juxtaposed to and extending between the inner faces of the sprockets are guide bars 200 which prevent the frames in the stack from becoming displaced as the stack is being lifted to elevated position (Fig. 2).

The upper shafts 191 also carry driving sprockets 202 and 204 which are respectively connected by chains 205 and 206 with speed reducers 208 and 210 (Fig. 2) connected to a common drive shaft 212 which carries a sheave 214. This sheave is equipped with a backstop to prevent reverse travel under the weight of the stack of frames and is driven by a motor 215 controlled by the switch S1. With this construction and arrangement the motor drives the sprocket 202 clockwise and the sprocket 204 counterclockwise, as viewed in Fig. 2.

Mounted on the upright channel 3 (Figs. 4 and 11) is a normally closed switch S2 having its operating lever positioned to be engaged and thus opened by one of the T-bars 198 as it is carried downwardly to the level of the lower shaft 190, as shown more clearly in Fig. 4. The switch S2 is connected in the control circuit (Fig. 13) of switch S1 and is operative to shut off motor 215 when the stack of frames has been elevated to the level of discharge opening D. Mounted at the upper end of the channel 3 is a normally closed switch S5 having its operating lever arranged to be engaged and thus opened by the uppermost frame of the stack lifted by the T-bars 198. The switch S5 is connected in the control circuit, hereinafter described, along with the switches S3, S4 and S6.

In normal operation the transfer of the twentieth frame closes the switch S1 and effects operation of the stack-lifting motor 215, whereupon sprockets 194 and 195 are rotated so as to elevate the stack-lifting bars 198 which raise the stack of twenty frames from the stationary dogs 74 to the level of discharge opening D, in which position a fork truck may remove them to an oven or other location, as previously explained. At the beginning of this operating cycle, the lower T-bar 198 disengages the operating lever of switch S2, thus closing the circuit to the motor 215 and as the switch S1 remains closed until another frame has been elevated by the carriages 68, the circuit to the motor remains closed. When the lifting bars 198 carrying the stack of frames reaches the level of the discharge opening D, switch S5 is opened and in the meantime the other lifting bar 198 has traveled downwardly to a position wherein it operates switch S2 to open the motor circuit, thus shutting off the motor as hereinabove more fully explained. The stack of frames is now supported at the level of the discharge opening and reverse travel of the stack is prevented by the backstop associated with sheave 214. Switch S5 remains open until the fork truck has removed the stack, after which it automatically closes.

Referring to Fig. 13, the control circuits for the stack-lifting mechanism and the conveyor motor CM operating the conveyor C are interconnected with each other as shown, it being noted that the power circuit is a three-phase system having the usual lines x, y and z connected through a solenoid-operated switch 225 with the conveyor motor CM and through a second sole-

soloid-operated switch 226 with the stack-lifting motor 215. One of the terminals of the solenoid 230 of switch 225 is connected with the line y and the other terminal is connected to a line in which the normally closed switches S3 to S6 are connected in series-parallel. This line is connected in series with the stop button 231 and the start button 232 which have the conventional connections with the power line. Depressing the start button closes the circuit through the solenoid 230 which actuates switch rod 234 to close the power circuit to conveyor motor CM, provided that the proper combination of switches S3 to S6 remain closed, in which case the motor CM is put into operation.

The switch 226 includes the usual solenoid 236 which operates switch rod 238 and one terminal of this solenoid is connected to the power line y and the other terminal to a branched circuit 240, one branch of which is connected through switch S2 in the usual manner to the power line. The other branch is connected with a conventional time-delay relay 242 (e. g. a G. E. type CR 7504) which includes the usual normally closed switch S7 in series with the normally open switch S1 which is connected in the usual manner to the power line. The switch S1 and associated parts are so designed that the switch S1 opens after a period of six to eight seconds and is not closed until switch S1 has been opened to reset the relay.

When the switch S1 is closed by the transfer of the twentieth frame, as above explained, the circuit through the solenoid 236 is closed and hence closes the power line to motor 215, whereupon the stack of frames is elevated. After six to eight seconds from the time the switch S1 is closed the switch S7 opens to cut the circuit through the switch S1, but prior to the expiration of the six to eight second period, the stack-lifting motor 215 has operated long enough to cause the lower bar 198 to disengage the operating lever of switch S2, which thereupon closes, thus maintaining the circuit through the solenoid 236 closed. When the stack has been elevated to the level of the discharge opening D, switch S2 opens and remains open until the next stack-lifting operation commences. Hence, after completing the stack-lifting operation, switches S2 and S7 remain open, thus breaking the circuit through the solenoid 236 and stopping the motor 215. The transfer of the next frame received from the conveyor operates the counter mechanism so as to open switch S1 and when the twentieth frame of the next group is transferred, switch S1 closes, and as the relay has now been reset, switch S7 is again closed for a period of six to eight seconds during which period the above described operation is repeated.

A résumé of the operation of the machine is as follows:

A frame F is received from the spray conveyor C and rides on driven rolls 22 which travel at a greater speed than the spray conveyor to pull the frame away from the latter. Upon entering the well W, the frame opens switch S4 which closes when the frame has been carried to the end of the well, at which time its leading edge engages the valve lever 111 of air valve 110 and the operating lever of switch S3 at the rear of the well. Actuation of the valve 110 operates control valve 115, thereby causing a single stroke (half cycle) of the piston 43.

The piston 43 operates through its connecting rod 42 and associated chain 40 to rotate the

sprockets 36 and 37 clockwise (Fig. 11) and thus rotate shafts 32 and 33 so as to cause the lifting carriages 68 to ride upwardly about twenty inches to lift the frame F slightly above the level of the dogs of the transfer carriages 70 which have been carried downwardly to their lowermost position below the level of stationary dogs 74.

When the piston 43 reaches the end of its forward stroke, the pin 122 carried by sprocket 37 engages the arm 121 of the valve 110 which operates the control valve 115 to admit air pressure to the other end of the cylinder, thereby causing the piston 43 to return to its original position. The return movement of the piston causes the sprockets and operating shafts to rotate clockwise (Fig. 11) thereby lowering the frame-lifting carriages 68 and elevating the transfer carriages 70. As the frame-lifting carriage is lowered, it transfers the frame to the carriages 70 which elevate it, together with the frames previously received and temporarily held on the fixed dogs 74, to a position above the latter, thereby completing the operating cycle. As the frame-lifting chain 64 returns to its lowermost position, the lug 170 carried thereby operates the counter mechanism 152.

The foregoing operating cycle is repeated twenty times and when the twentieth frame is transferred to the low stack, switch S1 closes the solenoid-operated switch 226 which starts the elevator motor 215, as above explained. When the stack reaches its top position the switch S2 opens the magnetic switch 226 to stop the motor 215, the time relay 242 being effective to prevent overtravel in case switch S1 were held closed after the switch S2 had been opened. The stack of twenty frames supported on the T-bars 198 is thus elevated and made ready to be picked up by the fork truck. The switch S5 is held open by the stack and automatically closes when the stack is removed. In the event a frame discharged from the spray conveyor C is not transferred to the stack, the switch S4 is opened by an incoming frame and the switch S3 is held opened by the frame which was not transferred. Hence, as both switches S3 and S4 are open, the circuit to the conveyor motor CM is broken and hence the conveyor motor is stopped and the power lines to motor 215 is broken. The trouble may then be rectified and normal operation resumed.

In the event the elevated stack is not timely removed by the fork truck, the switch S5 remains open and switch S6 (associated with the counter) opens after the eighteenth frame of the low stack is transferred to the stacking dog 74. If the upper stack is removed by the fork truck, S5 necessarily closes, but if not removed S5 remains open and when S6 opens the circuit to conveyor motor CM is broken and hence the operation of the spray conveyor is stopped as is also the elevator motor 215. Before the machine can resume normal operation, the elevated stack of frames must be removed by the fork truck, thereby closing switch S5 which permits the closed circuit through solenoid 230 to be reestablished by pressing the start button 232. Thereafter, normal operation is resumed and the nineteenth frame closes switch S6.

In the event the frames are not conveyed to the machine and the counter is on number twenty, the switch S1 is closed, but as switch S7 opens after six to eight seconds and as switch S2 is held open, the solenoid 236 remains de-

energized and the power circuit to the motor 215 remains open. The switches S2 and S7 remain open until the normal stacking operation is resumed, as above explained.

While I have shown and described one desirable embodiment of the invention it is to be understood that this disclosure is for the purpose of illustration and that various modifications may be made without departing from the spirit and scope of the invention as set forth in the appended claims.

I claim:

1. A machine for stacking frames and the like articles, comprising stationary upright members defining an elevator well having adjacent to its lower end an entrance opening to receive a frame and adjacent to its upper end a discharge opening through which a stack of frames may be withdrawn, stack-supporting means for holding a stack of frames at a level between the entrance and discharge openings, frame-lifting mechanism for elevating a frame received through the entrance opening and transferring it to said stack-supporting means, and a stack-lifting mechanism operative to elevate a stack of frames held by said stack-supporting means to a level within said elevator well at which it may be withdrawn through said discharge opening, said stack-lifting mechanism being operative to support said stack of frames at the last-mentioned level, thereby to permit operation of said frame-lifting mechanism to form another stack.

2. A machine for stacking frames and the like articles, comprising upright members defining an elevator well having adjacent to its lower end an entrance opening to receive a frame and adjacent to its upper end a discharge opening through which a stack of frames may be withdrawn, stack-supporting means for holding a stack of frames at a level between the entrance and discharge openings, frame-lifting mechanism for elevating a frame received through the entrance opening and transferring it to said stack-supporting means, a stack-lifting mechanism operative to elevate a stack of frames held by said stack-supporting means to a level at which they may be withdrawn through said discharge opening, said stack-lifting mechanism being operative to support said stack of frames at the last-mentioned level, thereby to permit operation of said frame-lifting mechanism to form another stack, control mechanism operative to actuate said frame-lifting and transferring mechanism when a frame is properly positioned within said well, and control mechanism operative when a predetermined number of frames have been transferred to said stack-supporting means to actuate said stack-lifting mechanism.

3. A machine for stacking frames and the like articles comprising stationary upright members defining an elevator well having adjacent to its lower end an entrance opening to receive a frame and adjacent to its upper end a discharge opening through which a stack of frames may be withdrawn, stack-lifting mechanism for elevating a stack of frames within said elevator well from a level above that of said entrance opening to the level of said discharge opening, and frame-lifting and transferring mechanism for elevating a frame received through said entrance opening and transferring it to said stack-lifting mechanism, said stack-lifting mechanism being operative to support said stack of frames at the level of said discharge opening, thereby to permit

5 operation of said frame-lifting and transferring mechanism to form another stack.

4. A machine for stacking frames and the like articles comprising upright members defining an elevator well having adjacent to its lower end an entrance opening to receive a frame and adjacent to its upper end a discharge opening through which a stack of frames may be withdrawn, stack-lifting mechanism for elevating a stack of frames from a level above that of said entrance opening to the level of said discharge opening, and frame-lifting and transferring mechanism for elevating a frame received through said entrance opening and transferring it to said stack-lifting mechanism, said stack-lifting mechanism being operative to support said stack of frames at the level of said discharge opening, thereby to permit operation of said frame-lifting and transferring mechanism to form another stack, conveying mechanism for delivering individual frames through said entrance opening, and control mechanism operative to actuate said frame-lifting and transferring mechanism in response to the delivery of a frame through said entrance opening.

5. A machine for stacking frames and the like articles comprising upright members defining an elevator well having adjacent to its lower end an entrance opening to receive a frame and adjacent to its upper end a discharge opening through which a stack of frames may be withdrawn, stationary latch dogs carried by said upright members for supporting a stack of frames at a level between the entrance and discharge openings, frame-lifting mechanism for elevating a frame received through said entrance opening to a level below said stationary latch dogs, frame-transferring mechanism vertically movable from a lowermost position, wherein it receives a frame elevated by said frame-lifting mechanism, to an uppermost position, wherein it transfers a frame to said stationary latch dogs, and stack-lifting mechanism for elevating a stack of frames supported by said stationary latch dogs to the level of said discharge opening, said stack-lifting mechanism being operative to support said stack of frames at the last-mentioned level, thereby to permit operation of said frame-lifting mechanism to form another stack.

6. A machine for stacking frames and the like articles comprising upright members defining an elevator well having adjacent to its lower end an entrance opening to receive a frame and adjacent to its upper end a discharge opening through which a stack of frames may be withdrawn, stationary latch dogs carried by said upright members for supporting a stack of frames at a level between the entrance and discharge openings, frame-lifting mechanism for elevating a frame received through said entrance opening to a level below said stationary latch dogs, frame-transferring mechanism vertically movable from a lowermost position, wherein it receives a frame elevated by said frame-lifting mechanism, to an uppermost position, wherein it transfers a frame to said stationary latch dogs, stack-lifting mechanism for periodically elevating a stack of frames supported by said stationary latch dogs to the level of said discharge opening, said stack-lifting mechanism being operative to support said stack of frames at the last-mentioned level, thereby to permit operation of said frame-lifting mechanism to form another stack, conveying mechanism for delivering individual frames through said entrance opening, and means effec-

tive upon delivery of a frame through said entrance opening to operate said frame-lifting mechanism and frame-transferring mechanism.

7. A machine for stacking frames and the like articles comprising upright members defining an elevator well having adjacent to its lower end an entrance opening to receive a frame and adjacent to its upper end a discharge opening through which a stack of frames may be withdrawn, stationary latch dogs carried by said upright members for supporting a stack of frames at a level between the entrance and discharge openings, frame-lifting mechanism for elevating a frame received through said entrance opening to a level below said stationary latch dogs, frame-transferring mechanism vertically movable from a lowermost position, wherein it receives a frame elevated by said frame-lifting mechanism, to an uppermost position, wherein it transfers a frame to said stationary latch dogs, stack-lifting mechanism for periodically elevating a stack of frames supported by said stationary latch dogs to the level of said discharge opening, said stack-lifting mechanism being operative to support said stack of frames at the last-mentioned level, thereby to permit operation of said frame-lifting mechanism to form another stack, control mechanism operative to actuate said frame-lifting mechanism when a frame is properly positioned within said well, and means operative after the transferring of a frame to said frame-transferring mechanism for effecting the operation of the latter mechanism.

8. A machine for stacking frames and the like articles comprising upright members defining an elevator well having adjacent to its lower end an entrance opening to receive a frame and adjacent to its upper end a discharge opening through which a stack of frames may be withdrawn, stationary latch dogs carried by said upright members for supporting a stack of frames at a level between the entrance and discharge openings, frame-lifting mechanism for elevating a frame received through said entrance opening to a level below said stationary latch dogs, frame-transferring mechanism vertically movable from a lowermost position, wherein it receives a frame elevated by said frame-lifting mechanism, to an uppermost position, wherein it transfers a frame to said stationary latch dogs, stack-lifting mechanism for elevating a stack of frames supported by said stationary latch dogs to the level of said discharge opening, said stack-lifting mechanism being operative to support said stack of frames at the last-mentioned level, thereby to permit operation of said frame-lifting mechanism to form another stack, control mechanism operative to actuate said frame-lifting mechanism when a frame is properly positioned within said well, means operative after the transferring of a frame to said frame-transferring mechanism for effecting the operation of the latter mechanism, and control mechanism operative when a predetermined number of frames have been transferred to said stationary latch dogs to actuate said stack-lifting mechanism.

9. A machine for stacking frames and the like articles comprising upright members defining an elevator well having adjacent to its lower end an entrance opening to receive a frame and adjacent to its upper end a discharge opening through which a stack of frames may be withdrawn, stationary latch dogs carried by said upright members for supporting a stack of frames at a level between the entrance and discharge

openings, frame-lifting mechanism including latch dogs vertically movable from a lowermost frame-receiving position to an uppermost position below said stationary latch dogs and back to the first position, transfer mechanism including latch dogs vertically movable from an uppermost position above the level of said stationary latch dogs to a lowermost position below the uppermost position of the latch dogs of said frame-lifting mechanism and back to the first position, and connections between said frame-lifting mechanism and transfer mechanism operative to lower said transfer mechanism as said frame-lifting mechanism moves upwardly, thereby to effect the transfer of a frame carried thereby, and to elevate said frame-transferring mechanism as said frame-lifting mechanism moves downwardly, thereby to position the frame at a level above said stationary dogs so that upon downward movement of said frame-transferring mechanism the frame carried thereby is transferred to said stationary dogs.

10. A machine for stacking frames and the like articles comprising upright members defining an elevator well having adjacent to its lower end an entrance opening to receive a frame and adjacent to its upper end a discharge opening through which a stack of frames may be withdrawn, stationary latch dogs carried by said upright members for supporting a stack of frames at a level between the entrance and discharge openings, frame-lifting mechanism including latch dogs vertically movable from a lowermost frame-receiving position to an uppermost position below said stationary latch dogs and back to the first position, transfer mechanism including latch dogs vertically movable from an uppermost position above the level of said stationary latch dogs to a lowermost position below the uppermost position of the latch dogs of said frame-lifting mechanism and back to the first position, connections between said frame-lifting mechanism and transfer mechanism operative to lower said transfer mechanism as said frame-lifting mechanism moves upwardly thereby to effect the transfer of a frame carried thereby, and to elevate said frame-transferring mechanism as said frame-lifting mechanism moves downwardly, thereby to position the frame at a level above said stationary dogs so that upon downward movement of said frame-transferring mechanism the frame carried thereby is transferred to said stationary dogs, and stack-lifting mechanism operative to lift a stack of frames transferred to said stationary dogs to the level of said discharge openings.

11. A machine for stacking frames and the like articles comprising upright members defining an elevator well having adjacent to its lower end an entrance opening to receive a frame and adjacent to its upper end a discharge opening through which a stack of frames may be withdrawn, stationary latch dogs carried by said upright members for supporting a stack of frames at a level between the entrance and discharge openings, frame-lifting mechanism including latch dogs vertically movable from a lowermost frame-receiving position to an uppermost position below said stationary latch dogs and back to the first position, transfer mechanism including latch dogs vertically movable from an uppermost position above the level of said stationary latch dogs to a lowermost position below the uppermost position of the latch dogs of said frame-lifting mechanism and back to the first position, connections between said frame-lifting mechanism

and transfer mechanism operative to lower said transfer mechanism as said frame-lifting mechanism moves upwardly thereby to effect the transfer of a frame carried thereby, and to elevate said frame-transferring mechanism as said frame-lifting mechanism moves downwardly, thereby to position the frame at a level above said stationary dogs so that upon downward movement of said frame-transferring mechanism the frame carried thereby is transferred to said stationary dogs, and stack-lifting mechanism operative after a predetermined number of frames have been transferred to said stationary dogs to lift the stacks of frames to the level of said discharged openings.

12. A machine for stacking frames and the like articles comprising upright members defining an elevator well having adjacent to its lower end an entrance opening to receive a frame, stationary latch dogs carried by said upright members for supporting a stack of frames at a level above said entrance opening, frame-lifting mechanism including latch dogs vertically movable from a lowermost frame-receiving position to an uppermost position below said stationary latch dogs and back to the first position, transfer mechanism including latch dogs vertically movable from an uppermost position above the level of said stationary latch dogs to a lowermost position below the uppermost position of the latch dogs of said frame-lifting mechanism and back to the first position, connections between said frame-lifting mechanism and transfer mechanism operative to lower said transfer mechanism as said frame-lifting mechanism moves upwardly thereby to effect the transfer of a frame carried thereby, and to elevate said frame-transferring mechanism as said frame-lifting mechanism moves downwardly, thereby to position the frame at a level above said stationary dogs so that upon downward movement of said frame-transferring mechanism the frame carried thereby is transferred to said stationary dogs, conveying mechanism for delivering individual frames through said entrance openings, and mechanism for automatically operating said frame-lifting and said frame-transferring mechanisms in response to the delivery of a frame through said entrance opening.

13. A machine for stacking frames and the like articles comprising upright members defining an elevator well having adjacent to its lower end an entrance opening to receive a frame, stationary latch dogs carried by said upright members for supporting a stack of frames at a level above said entrance opening, a plurality of pairs of interconnected vertically movable, oppositely travelling reciprocating members, the corresponding members of each pair of having frame-lifting latch dogs movable from a lowermost position in which they receive a frame delivered through said entrance opening to an uppermost position below said stationary latch dogs, the other corresponding members of each pair having frame-transfer latch dogs movable from an uppermost position above said stationary latch dogs to a lowermost position below the uppermost position of said frame-lifting latch dogs, the upward movement of said frame-transfer latch dogs being effective to transfer a frame carried by said frame-lifting latch dogs to said frame-transfer latch dogs and the subsequent downward movement of said frame-transfer latch dogs being effective to transfer the frame carried by said frame-lifting latch dogs to said frame-transfer latch dogs and the subsequent downward move-

ment of said frame-transfer latch dogs being effective to transfer the frame carried thereby to said stationary latch dogs.

14. A machine for stacking frames and the like articles comprising upright members defining an elevator well having adjacent to its lower end an entrance opening to receive a frame and adjacent to its upper end a discharge opening through which a stack of frames may be withdrawn, stationary latch dogs carried by said upright members for supporting a stack of frames at a level between the entrance and discharge openings, a plurality of pairs of interconnected vertically movable oppositely travelling reciprocating members, the corresponding members of each pair having frame-lifting latch dogs movable from a lowermost position in which they receive a frame delivered through said entrance opening to an uppermost position below said stationary latch dogs, the other corresponding members of each pair having frame-transfer latch dogs movable from an uppermost position above said stationary latch dogs to a lowermost position below the uppermost position of said frame-lifting latch dogs, the upward movement of said frame-transfer latch dogs being effective to transfer a frame carried by said frame-lifting latch dogs to said frame-transfer latch dogs and the subsequent downward movement of said frame-transfer latch dogs being effective to transfer the frame carried thereby to said stationary latch dogs, and stack lifting mechanism operative to elevate a stack of frames supported by said stationary latch dogs to the level of said discharge opening.

15. A machine for stacking frames and the like articles comprising upright members defining an elevator well having adjacent to its lower end an entrance opening to receive a frame, stationary latch dogs carried by said upright members for supporting a stack of frames at a level above said entrance opening, a plurality of pairs of vertically movable oppositely travelling, reciprocating chains, one chain of each pair carrying frame-lifting latch dogs movable from a lowermost position in which they receive a frame delivered through said entrance opening to an uppermost position below said stationary latch dogs, the other chain of each pair carrying frame-transfer latch dogs movable from an uppermost position above said stationary latch dogs to a lowermost position below the uppermost position of said frame-lifting latch dogs, the upward movement of said frame-transfer latch dogs being effective to transfer a frame carried by said frame-lifting latch dogs to said frame-transfer latch dogs and the subsequent downward movement of said frame-transfer latch dogs being effective to transfer the frame carried thereby to said stationary latch dogs.

16. A machine for stacking frames and the like articles comprising upright members defining an elevator well having adjacent to its lower end an entrance opening to receive a frame and adjacent to its upper end a discharge opening through which a stack of frames may be withdrawn, stationary latch dogs carried by said upright members for supporting a stack of frames at a level between the entrance and discharge openings, a plurality of pairs of vertically movable oppositely travelling, reciprocating chains,

one chain of each pair carrying frame-lifting latch dogs movable from a lowermost position in which they receive a frame delivered through said entrance opening to an uppermost position below said stationary latch dogs, the other chain of each pair carrying frame-transfer latch dogs movable from an uppermost position above said stationary latch dogs to a lowermost position below the uppermost position of said frame-lifting latch dogs, the upward movement of said frame-transfer latch dogs being effective to transfer a frame carried by said frame-lifting latch dogs to said frame-transfer latch dogs and the subsequent downward movement of said frame-transfer latch dogs being effective to transfer the frame carried thereby to said stationary latch dogs, and stack-lifting mechanism operative after a predetermined number of frames have been transferred to said stationary latch dogs to elevate the stack of frames supported thereby to the level of said discharge opening.

17. A machine for stacking frames and the like articles comprising upright members defining an elevator well having adjacent to its lower end an entrance opening to receive a frame, stationary latch dogs carried by said upright members for supporting a stack of frames at a level above said entrance opening, frame lifting mechanism comprising horizontal shafts mounted in vertically aligned pairs adjacent to opposite ends of said well above and below said entrance opening, a pair of relatively large sprockets carried by opposite ends of each shaft and a pair of relatively small sprockets carried by the opposite ends of each shaft, the large sprockets being arranged in vertically aligned pairs and the small sprockets being arranged in vertically aligned pairs juxtaposed to the large sprockets, vertically disposed chains extending about each pair of large and small sprockets, the chains associated with the large sprockets carrying horizontally aligned frame-lifting latch dogs arranged to engage the marginal portions of the under surface of the frame received through said entrance opening so as to lift the frame to an uppermost position slightly below the level of said stationary latch dogs when said shafts are rotated in one direction, the chains associated with the smaller sprockets carrying horizontally aligned frame-transfer latch dogs arranged to travel from an uppermost position slightly above said stationary latch dogs to a lowermost position slightly below the uppermost position of said frame-lifting latch dogs when said shafts are rotated in said one direction and from the latter position back to the former position when said shafts are rotated in the opposite direction, thereby to effect the transfer of a frame from said frame-lifting latch dogs to said stationary latch dogs, and motor mechanism for effecting a predetermined rotation of said shafts in one direction and then in the other direction.

18. A machine for stacking frames and the like articles comprising upright members defining an elevator well having adjacent to its lower end an entrance opening to receive a frame and adjacent to its upper end a discharge opening

through which a stack of frames may be withdrawn, stationary latch dogs carried by said upright members for supporting a stack of frames at a level between the entrance and discharge openings, frame-lifting mechanism comprising horizontal shafts mounted in vertically aligned pairs of adjacent to opposite ends of said well above and below said entrance opening, a pair of relatively large sprockets carried by opposite ends of each shaft and a pair of relatively small sprockets carried by the opposite ends of each shaft, the large sprockets being arranged in vertically aligned pairs and the small sprockets being arranged in vertically aligned pairs juxtaposed to the large sprockets, vertically disposed chains extending about each pair of large and small sprockets, the chains associated with the large sprockets carrying horizontally aligned frame-lifting latch dogs arranged to engage the marginal portions of the under surface of the frame received through said entrance opening so as to lift the frame to an uppermost position slightly below the level of said stationary latch dogs when said shafts are rotated in one direction, the chains associated with the smaller sprockets carrying horizontally aligned frame-transferring latch dogs arranged to travel from an uppermost position slightly above said stationary latch dogs to a lowermost position slightly below the uppermost position of said frame-lifting latch dogs when said shafts are rotated in said one direction and from the latter position back to the former position when said shafts are rotated in the opposite direction, thereby to effect the transfer of a frame from said frame-lifting latch dogs to said stationary latch dogs, motor mechanism for effecting a predetermined rotation of said shafts in one direction and then in the other direction, and stack-lifting mechanism for elevating a stack of frames supported by said stationary latch dogs to the level of said discharge opening.

19. A stacking machine as set forth in claim 1, which includes control mechanism associated with the frame-lifting mechanism and operative to arrest the operation of said frame-lifting mechanism in event a frame supported thereby is not transferred to the stack-supporting means.

20. A stacking machine as set forth in claim 1, which includes control mechanism associated with the frame-lifting and stack-lifting mechanisms and operative to arrest their operations in event a stack of elevated frames is not removed through the discharge opening after a predetermined period of operation of said mechanisms.

ROGER L. GRIFFIN.
